(57) **CLAIM**

The ornamental design for a leg support harness, as shown and described.

DESCRIPTION

FIG. 1 is a front perspective view of a fourth embodiment of the leg support harness, with environment, showing my new design;

FIG. 2 is a front perspective view of a fourth embodiment of the leg support harness, showing my new design;

FIG. 3 is a left side view of a fourth embodiment of the leg support harness shown in FIG. 2, showing my new design;

FIG. 4 is a front view of a fourth embodiment of the leg support harness shown in FIG. 2, showing my new design;

FIG. 5 is a right side view of a fourth embodiment of the leg support harness shown in FIG. 2, showing my new design;

FIG. 6 is a rear view of a fourth embodiment of the leg support harness shown in FIG. 2, showing my new design;

FIG. 7 is a front perspective view of a fourth embodiment of the leg support harness shown in FIG. 2 in an open position, showing my new design; and,

FIG. 8 is a rear perspective view of a fourth embodiment of the leg support harness shown in FIG. 2 in an open position, showing my new design.

The broken lines in the drawing depict environmental subject matter only and form no part of the claimed design.
